SLEEPING GARMET

Louis W. Helmuth, Lakewood, Ohio

Application August 16, 1937, Serial No. 159,218

2 Claims. (Cl. 2—114)

This invention relates to new and useful improvements in sleeping garments.

An important object of the invention is to provide a comfortable sleeping garment with an open skirt effect with no crotch, and to make this skirt effect assimilate pants, shorts, pajamas or the like.

Other objects and advantages of the invention will become apparent during the course of the following description.

In the accompanying drawings forming a part of the application and wherein like numerals are employed to designate like parts throughout the several views,

15 Fig. 1 is a front plan of one form of the invention of the knee length type,

Fig. 2 is a side elevation of the same,

Fig. 3 is a bottom elevation of the lower end of the garment,

20 Fig. 4 is a front plan of a modified form of the invention showing the pajama length type of garment,

Fig. 5 is a side elevation of the same,

Fig. 6 is a bottom plan of the same.

25 As stated, the primary object of the invention is to provide a comfortable sleeping garment with an open skirt effect and to make this skirt effect assimilate shorts or pajamas. Referring to the figures in general, the garment comprises a sub-

stantially open ended tubular body portion 10 and skirt portion 10'. This skirt portion may be of any length desired, but at least approximately of knee length or thereabouts. The modifications shown in Figs. 4 to 6 illustrate the skirt portion of

35 a length below the knees. The neck opening 11 in the body portion may be of any shape or style and this upper shirt end of the garment may be sleeveless or have sleeves 12 of any desired length or kind, preferably of the raglan or kimona style.

40 In order that the lower skirt portion 10' of the garment be camouflaged to assimilate shorts or pajamas for persons who are fastidious about their nightly appearance, the front and back panels or portions 13 and 14 respectively of the skirt portion are each provided with a demarcation or ornamentation 15 to give the appearance of the two leg portions of shorts or pajamas.

45 In Figs. 1 to 3, this demarcation 16 takes the form of a vertical relatively wide stripe to give the appearance of the garment having a crotch and a pair of leg portions, while actually, it has no crotch. This demarcation may be of any desired shape, but an inverted solid V-shape, gives 50 the effect, or an inverted V-shape with a pair of

separated upwardly converging stripes or legs 17 continuing around the lower edge of the skirt, as shown in Figs. 4 to 6 inclusive, is also effective in giving a more decided appearance of pants legs. The stripes 16 and 17 of color contrasting with the skirt material, are preferably trimming bands sewed on to the skirt material so as to assist in causing the skirt to hang relatively flat in a manner to expose the stripes when the garment is donned by the wearer. To augment this purpose, these stripes may be of heavier or stiffer material than the garment itself, or it may be spun or woven in a different way than the garment material or as integral parts of the skirt to get the same results. In case these stripes are 10 printed directly upon the garment fabric, the coloring material, will of itself, add to the thickness, density or bulk of those portions of the garment material upon which the trimmings are disposed to, in effect, stiffen the skirt and cause 15 it to hang in a manner to expose the stripes. The stripes around the bottom edges of the skirt, augment this purpose. In some forms of the invention the skirt may be made to hang with an inverted V-shaped fold or kick pleat at the front 20 and back folded inwardly at the lower edge of the skirt and extending up to a point adjacent the wearer's crotch. In such cases that portion of the skirt defined down within the V-shaped fold is colored a contrasting color. Any of these 25 forms may have the addition of a vertical slot 19, of any desired length, separating each front and rear skirt portion into leg portions 20 and 21 to render the pants effect more pronounced. The two sides of the skirt portion 10' may each be 30 provided with a slit or slot 22 bordered with a continuation 22' of the stripe or band from around the lower edge up to the vicinity of the hip of the wearer to give greater freedom of body parts within the garment and to enhance the appearance thereof, or the sides of the garment may be entirely closed. The back panel may have a similar vertical stripe from the lower edge up to a point about the middle of the skirt portion, or this vertical stripe may be augmented with a 35 small horizontal stripe at the upper end of the vertical stripe to form substantially a T or Y effect.

The mid-section of the body part may also be provided with a belt effect 23 at waist height to 50 give the garment the effect of being composed of an upper shirt piece and lower pants piece. The belt effect and demarcations 16, 17, and 22' may be printed directly upon or incorporated directly in the fabric by any known methods of 55

obtaining color effects. To accentuate this effect, the shirt and pants portions may be made of different colors, designs or striping by such methods. The neck band and cuffs of the sleeve 5 may be ornamented with a colored band or other trimming to further assimilate the pajama shirt effect. Either the short or the long pants type 10 may be slotted or slit only upon their sides, or only up the middle of the front and rear skirt panels to a point well below the wearer's crotch with the trimming 16 or 17 extending farther toward the actual crotch of the wearer, as shown, or may be slit or slotted both upon the sides and 15 the front and rear panels as desired. As shown in Fig. 4, the inverted V-shaped slot 19 terminates at a point below the wearer's crotch, leaving the skirt with an apron portion covering the wearer's crotch to make the garment modest. In this figure 20 it will be noted that the trimming 17 bordering the slot 19 extends farther toward the actual crotch of the wearer than the slot. The effect is accentuated by extending the trimming to the point where the wearer's crotch is actually disposed, as shown in Fig. 1, as this gives the effect of the 25 slot extending all the way up to the wearer's crotch without its actually doing so, so that an entirely modest garment is provided.

Other changes in the size, shape and relationship of parts and ornamentation may be resorted to without departing from the spirit of the invention or the scope of the appended claims.

I claim:

1. A sleeping garment comprising an open tubular skirt of at least knee length, the front of the skirt having its lower edge at the middle of the front provided with a slit extending from the bottom edge of the skirt toward the crotch of the wearer but terminating below the same to leave the skirt with an apron portion covering the wearer's crotch, the skirt continuing unbroken at the sides thereof, and said skirt having a color contrasting with that of the garment extending from the top of the slot to a point closer to the wearer's crotch than the top of the slit and to approximately the wearer's crotch to form, in effect, a continuation of the slit effect substantially up to the point of the wearer's crotch. 15

2. A sleeping garment comprising an open tubular skirt of at least knee length, the middle of the lower edge of the front and back of the skirt each having a slot extending from the bottom edge and dividing the skirt into a pair of side panels extending continuously around the sides, said slot terminating at a point below the wearer's crotch to reserve an apron portion covering the wearer's crotch, and a trimming of contrasting color extending along the sides of the slot and the trimming extending from the top of the slot to a point closer to the wearer's crotch than the top of the slot to form, in effect, a continuation of the slot effect up to the wearer's crotch. 20 25
